STAPLE-FORMING MACHINE

John H. Mott, Upper Merion, Pa.

Application October 26, 1955, Serial No. 542,822

12 Claims. (Cl. 1-2)

The present invention relates to staple-forming machines and is concerned primarily with a staple-forming machine that is adapted to be attached to a staple-driving machine.

At the present time there are many types of staple-driving machines. One staple driver that is now meeting with widespread use particularly in the field of packaging is the so-called retractable anvil stapling machine. Retractable anvil stapling machines are commonly employed where access may be had to only one side of the material being stapled, such as in the closing of cartons. This type of stapling machine uses what is known as an industrial staple. Such a staple is fairly heavy and is made from a flat wire. In accordance with present-day practice, staples are supplied to retractable anvil stapling machines in magazines which consist of long strips of preformed staples.

There are today many installations of retractable anvil stapling machines which are automatic; thus, when a carton having one or more sets of flaps which are to be closed reaches the stapling station, one or more heads automatically engage the flaps and perform the staple-driving operations. With such automatic machines, it is evident that any given magazine of staples is quickly expended, and it requires the attention of an operator to replace them at frequent intervals.

With the foregoing conditions in mind, the present invention has in view as its foremost objective the provision of a staple-forming machine that is particularly adapted to be attached to and combined with a staple-driving machine.

More in detail, the invention has as an object the provision of a staple-forming machine that is adapted to be combined with a staple-driving machine in such a manner that the operation of the staple-forming machine is correlated and synchronized with that of the staple-driving machine.

A somewhat more detailed object of the invention is to provide a staple-forming machine that is particularly adapted to be attached to and combined with a staple-driving machine of the retractable anvil type. Such a staple-driving machine utilizes an industrial staple, and the staple-forming machine of this invention is particularly adapted to making an industrial staple and forming this staple in proper relation with respect to the operation of the retractable anvil staple-driving machine.

In a retractable anvil staple-driving machine, a plunger is driven downwardly to carry out the various actions involved in the staple-driving operation. This plunger must be driven from an appropriate power source. While there are retractable anvil stapling machines of the manually operable type, there are also many automatic installations of such a stapling machine. One type of automatic installation now meeting with widespread use employs an air cylinder as the motivating force. The piston of this air cylinder is connected to the plunger of the stapling machine by a bell crank.

2

With this condition in mind, another highly important object of this invention is to provide a staple-forming machine that is adapted to be attached to and combined with a staple-driving machine in such a manner as to utilize the power source which operates the stapling machine for the motivating force which operates the staple-forming machine.

More in detail, the invention has as an object the provision of a staple-forming machine that is adapted to be attached to and combined with a retractable anvil stapling machine which is operated from an air cylinder, with the staple-forming machine being operatively connected to the bell crank which connects the piston of the air cylinder to the plunger of the stapling machine so as to be driven thereby.

Another object of this invention is to provide a staple-forming machine of the character indicated which forms staples from a long strip of flat wire that is wound into a reel or spool that is supported in a position conveniently close to the staple-forming machine. From the very nature of the staple-forming operation, an appropriate length must be cut from this wire strip to form each staple. Moreover, it is to be remembered that the wire is heavy because industrial staples are to be formed therefrom. Thus, it is important that the end portion of this wire be securely gripped and held while it is cut from the main body portion of the wire, and during the staple-forming operation.

With this factor in mind, a further object of the invention is to provide in a staple-forming machine of the character indicated a mandrel over which the end portion of the wire is positioned as it is cut. Cooperating with this mandrel is a pusher which engages the edge of the wire under spring pressure and a pressure bar which engages the top surface of the wire and forces it against the mandrel under spring pressure as the wire is cut and formed.

Another object is to provide in a staple-forming machine of the character indicated a frame, together with a slide that is reciprocal in the frame. This slide is connected to the bell crank, which connects the piston of the air cylinder to the plunger of the stapling machine. Cooperating elements of a shear are mounted on the slide and frame, respectively, so as to cut off the end portion of the wire on each downward stroke of the slide.

Still another object of the invention is to provide in a staple-forming machine of the character aforesaid, forming elements which are carried by the slide, and which cooperate with the mandrel to fashion the cutoff piece of wire into the U-shape which is characteristic of an industrial staple. This U-shape provides a staple having a back and a pair of legs depending therefrom.

Industrial staples are ordinarily made from a steel wire having properties of resiliency and elasticity. The forming elements bend the legs into positions substantially normal to the back. When these forming elements are removed, the resilient and elastic properties of the steel create a tendency for these legs to spring back into a position out of the perpendicular. This is undesirable. Thus, another object of the invention is to provide in a staple-forming machine of the character aforesaid a mandrel having a concave top surface in which the back of the staple is adapted to be forced during the staple-forming operation to form a bowed or concave staple back. When the staple-forming elements are removed, these same resilient and elastic properties are present in the concave back, and offset or counteract the tendency of the legs to spread outwardly. Thus, a staple is accurately formed with the legs assuming the right-angular relation to the back. Particular objects and advantages of the invention are associated with the provision of in-

strumentalities for accurately controlling the extent to which the back is deformed.

In accordance with the present invention, the wire is gripped under spring pressure from its side edge and top face, cut off, and formed into a staple on the downward stroke of the slide. On the upward stroke, the formed staple is advanced towards the head of the stapling machine a distance of about one half inch, which is in excess of the width of the staple, and the wire again fed into the machine its required length. An important object of this invention is to provide instrumentalities which are operatively connected to the slide for carrying out these operations.

More in detail, the invention has as an object the provision of a staple-forming machine of the character indicated and which includes a mandrel on which is slidably mounted a pusher. This pusher is of a U-shaped cross section substantially corresponding to that of a formed staple, and is spring-biased so that it is normally urged toward the head of the stapling machine. A lever has one end pivotally mounted in fixed position on the frame of the machine and its other end is operatively connected to the slide. This lever carries abutment elements which are adapted to be engaged by certain cams so as to control the movements of the pusher.

Another object of the invention is to provide in a staple-forming machine of the type aforesaid a shaft that is mounted in the frame and which is operatively connected to the slide. Surrounding this shaft is a sleeve. A pawl-and-ratchet mechanism is employed to operatively connect the sleeve to the shaft only on the upstroke of the slide. This shaft and sleeve carry the cams aforesaid which engage the abutments on the lever and thus control the movement of the pusher.

Still another object in view is to provide in a staple-forming machine of the type indicated, a drum which is disposed about the sleeve. A portion of this drum is formed as a feed wheel which engages the wire from the supply roll to feed it into the machine when the drum rotates. A clock spring has one end anchored to the drum and its other end to the sleeve. The drum is held against rotation during the downstroke and the major part of the upstroke of the slide, and during this upstroke the spring is cocked or loaded so that when it is released at the end of the upstroke the drum is rotated under the influence of the spring to feed the wire to the machine. Important features of the invention are associated with the mechanism provided for controlling the operation of the drum.

Various other more detailed objects and advantages of the invention such as arise in connection with carrying out the above-noted ideas in a practical embodiment will in part become apparent and in part be hereinafter stated as the description of the invention proceeds.

The invention, therefore, comprises a staple-forming machine that is adapted to be attached to and combined with a retractable anvil stapling machine, and which staple-forming machine includes a slide that is actuated from the power source of the stapling machine, and which slide operates the various instrumentalities which enter into and perform the staple-forming operation.

For a full and more complete understanding of the invention, reference may be had to the following description and accompanying drawings wherein:

Figure 1 is a bottom plan view of the staple-forming machine of this invention as applied to a retractable anvil stapling machine.

Figure 2 is a vertical longitudinal section through the staple-forming machine, with the stapling machine shown in elevation and with parts in the background omitted, and is taken about on the plane represented by the line 2-2 of Figure 1.

Figure 3 is a longitudinal vertical section through the drum, sleeve and associated instrumentalities of the

staple-forming machine, and is taken about on the plane represented by the line 3-3 of Figure 1.

Figure 4 is a detailed vertical section through the mandrel, and is taken about on the planes represented by the lines 4-4 of Figure 2.

Figure 5 is a transverse vertical section taken about on the plane represented by the line 5-5 of Figure 1.

Figure 6 is another transverse vertical section taken about on the plane represented by the line 6-6 of Figure 1.

Figure 7 is still another transverse vertical section taken about on the plane represented by the line 7-7 of Figure 1.

Figure 8 is another transverse vertical section taken about on the plane represented by the line 8-8 of Figure 1.

Figure 9 is a detailed rear end elevation taken about on the plane represented by the line 9-9 of Figure 1.

Figure 10 is a detailed horizontal section taken about on the plane represented by the line 10-10 of Figure 9; and

Figure 11 is a perspective view illustrating the slide and certain of the instrumentalities that are associated therewith. This view is somewhat diagrammatic and does not accurately conform to the proportions for purposes of clarity.

The stapling machine

While the staple-forming machine of this invention is readily adapted to be combined with various types of stapling machines, it has been particularly designed for attachment to a retractable anvil stapling machine which is operated by an air cylinder. Those portions of such a retractable anvil stapling machine which are pertinent to the present staple-forming machine will now be described.

The stapling machine includes a head 10 which is connected at the bottom to a penetration control mechanism designated 11. Reciprocally mounted in the head 10 is a plunger 12 which operates the staple-driving mechanism. Mounted on the rear face of the head 10 is a supporting bracket 13 which carries an air cylinder 14. Connected to the piston (not illustrated) of the air cylinder 14 is a rod 15. The outer free end of this rod 15 is connected by links 16 to a bell crank 17. The latter is pivotally mounted on a shaft 18 that is supported in openings 19 in the supporting bracket 13 (see Figures 6 and 7). The front end of the bell crank 17 is pivotally connected as indicated at 21 to links 22 which are in turn pivotally connected to the plunger 12 as indicated at 23. It is evident that as the piston within the air cylinder 14 is reciprocated, the bell crank 17 is actuated to reciprocate plunger 12 and thus operate the stapling machine.

Frame of staple-forming machine

The frame of the staple-forming machine is referred to in its entirety by the reference character F. The frame F includes a pair of ears 24 and 25 that are formed with openings which receive the opposite end portions of the shaft 18. Thus, the frame F is supported from the shaft 18 and by the head 10 to which it is connected by the screws shown at 9. Extending downwardly from the ear 24 there is a side wall 26, while a domelike wall 27 extends outwardly from the ear 25. An L-shaped bracket having a vertical wall 28 and a horizontal wall 29 extends across the front of the forming machine with the front edge of the wall 29 abutting the head 10 and attached to head 10 as indicated at 30. This bracket wall 28 has an extension shown at 31 which extends out in front of the dome 27.

The frame also includes a vertical partition shown at 32 in Figure 2 and a rear wall 33. There is other wall structure that is connected to these parts that will later become apparent.

A mandrel is referred to in its entirety by the reference character M. This mandrel M has a vertical cross section somewhat similar to a hat that is defined by a top wall 34

and side walls 35 from which outwardly extend flanges 36. The front end of the mandrel M is mounted on a block 37 that is secured to the rear face of the head 10 immediately below the opening through which a formed staple is fed to the machine. The flanges 36 are secured to the frame by the screws shown at 38 in Figure 4.

It will be noted from Figure 2 that the mandrel M extends from the head 10 rearwardly past the partition 32. Extending downwardly from the top wall 34 of the mandrel M is a spring anchor 39 to which is anchored one end of a tension coil spring 40 having a purpose to be later described. It is important to note that the top wall 34 is slightly concave, or in the form of a shallow V as illustrated. This enters into the formation of the staple, as will be later pointed out.

Slidably mounted on the top of the mandrel M is a pusher 41 of U-shaped cross section. This pusher carries a pin 42 which extends below the back of the pusher as shown in Figure 2 to constitute a spring anchor, and above the pusher as shown in Figures 9, 10, and 11, where it is adapted to be engaged by an operating lever as will be later pointed out. The tension spring 40 has its other end secured to this pin 42 as shown in Figures 2 and 9. Thus, the spring 40 normally biases the pusher 41 inwardly toward the head 10.

The slide

A slide which is an essential part of the staple-forming machine is referred to in its entirety by the reference character S. The slide S includes a main body portion 43 which operates between ball races 44 that are mounted on the frame wall 28. Extending upwardly from the main body portion 43 of the slide S is a tongue 45 which passes through an opening 46 formed in the supporting bracket 13 of the stapling machine. Pivotaly connected to this tongue by pin 47 are links 48 which are in turn connected to the bell crank 17 by pin 49. Thus the slide S is operatively connected to the bell crank 17 to be actuated thereby.

The front face of the slide S is disposed closely adjacent to the frame wall 28. The rear face of the main body portion 43 of this slide is formed with a depression or recess 50 for a purpose to be later described. Extending outwardly from one side of the main body portion 43 of the slide is a wing 51 that is formed with an open mouth slot for a purpose to be later described.

Extending downwardly from the main body portion 43 of the slide are two legs 53 and 54 (see Figure 5) which are spaced apart a sufficient distance to appreciably clear the mandrel M.

An element of a shear is shown at 55 and is carried by a plate 56 that is secured to the frame wall 31. Cooperating with the shear element 55 is a complementary shear element 57 that is mounted on the leg 54 of the slide. The lower edge of this element 57 also constitutes a forming element as will be later described.

Another forming element 58 is carried by the leg 53 of the slide.

Referring now more particularly to Figure 2, a bracket 59 has a foot 60 that is secured to the main body portion 43 of the slide S immediately above the recess 50. This bracket 59 extends rearwardly, downwardly, and then rearwardly again to provide an arm 61, on the free rear edge of which is pivotally mounted a bell crank 62 (see Figure 7). The bell crank 62 has two arms 63 and 64. The arm 63 is adapted to be engaged by an abutment pin 65 that is fixedly mounted on the frame F at the end of the downstroke. The arm 64 is adapted to engage a drum-holding pawl 66 at the end of the upstroke, as will later become apparent. A U-shaped spring 67 has one end secured to the arm 64 as shown at 68 and its other end to the bracket 59 as shown at 69. This spring 67 serves to bias the bell crank 62 and hold it on one side or the other of dead center.

Pressure bar

A pressure bar is referred to in its entirety by the reference character P. It is more clearly illustrated in Figures 2 and 11. The pressure bar P has the general construction of a bell crank defined by a horizontal arm 70 that is pivotally mounted on a pin 71, which is in turn fixedly mounted in the frame F. Upstanding from the front end of the horizontal arm 70 is a vertical arm 72, the upper end of which is bifurcated as indicated at 73. The bifurcated end of the arm 72 carries a roller 74 which is adapted to ride over into the recess 50 of the slide S when the latter is moved down opposite to the roller 74.

The lower front edge of the arm 70 is formed as a rib 75 that is adapted to bear against the top face of the wire as the latter is positioned over the top wall 34 of the mandrel M.

An adjusting screw 76 is mounted in a threaded opening in the partition 32 and carries a pin 77 which functions as a spring seat. Another spring seat 78 is carried by the arm 72. An expansion coil spring 79 has its opposite ends seated over the pins 77 and 78. This spring 79 exerts a tendency to urge the arm 72 forwardly and thus rotate the pressure bar P about the pin 71 as an axis. This action is made possible when the roller 74 rides into the recess 50. When the roller is in this position, the spring 79 forces the rib 75 downwardly against the wire.

It is evident that by adjusting the screw 76, the effective tension of the spring 79 may be adjusted. With the rib 75 being slightly convex in a shape complementary to the concave top wall 34 of the mandrel M, it is evident that the back of the staple formed will be imparted a corresponding curvature. It is the effective pressure of the spring 79 which determines the extent to which the back of the staple is bowed.

Shaft, sleeve, drum, and associated mechanism

Referring now more particularly to Figure 3, the frame F is shown as including a vertical wall 80 that is spaced from and located in alignment with the extension 31. A shaft 81 has one end journaled in the wall 33 and its opposite end reduced and journaled in the frame wall 80. Disposed about the shaft 81 is a sleeve 82 which is rotatably mounted on the shaft 81 through the medium of needle bearings shown at 83. The rear end of this sleeve 82 is enlarged into the cup-shaped formation illustrated at 84, and the free edge of the cup-shaped portion 84 is formed as a four-lobe cam 85. A second cam 86 is drivably mounted on the shaft 81 as illustrated at 87. The purpose of these cams 85 and 86 will later become apparent.

A drum is referred to in its entirety by the reference character D. This drum D is rotatably mounted on the sleeve 82 through the medium of the ball-bearing assemblies indicated at 8. The drum D includes a feed wheel 88 which cooperates with a roller 89 that is carried by stub shaft 90 that extends inwardly from the frame wall 80. The wire, which is represented at 91, passes between the roller 89 and the feed wheel 88, the moving force being supplied by the feed wheel.

The drum D also includes a ratchet part 92. As shown in Figure 7, the ratchet part 92 presents four shoulders 93, any one of which is adapted to be engaged by the free end of the drum-holding pawl 66. The latter is pivotally mounted at 94 on the frame F, and a tension coil spring 95 has one end secured to one end of the pawl 66 as indicated at 96 and its other end to the frame of the machine as indicated at 97. This spring 95 normally biases the effective end of the pawl 66 inwardly into the position in which it engages one of the shoulders 93 to hold the drum against rotation. The pawl 66 is also formed with a shoulder at 98 that is adapted to be engaged by the end of the arm 64 of the bell crank 62 so as to rotate the pawl 66 against the

influence of the spring 95 and release the effective end of the pawl from engagement with any shoulder 93 which it happens to abut.

A clock spring 99 has its inner end anchored to the sleeve 82 as shown at 100 and its outer end to the drum portion 92 of the drum D, as by the pin 101. This clock spring is initially placed under a required tension and is adapted to be further tensioned by rotation of the sleeve 82 on the upstroke of the slide. During such tensioning, the drum is held against rotation by the pawl 66; however, when the pawl 66 is knocked out of engagement with the ratchet 92 at the end of the upstroke, the spring 99 having been charged, will rotate the drum through 90° and feed a required length of wire to the machine.

Referring now more particularly to Figure 5, which may be considered along with Figure 3, the shaft 81 is shown as carrying a bell-crank-shaped lever having arms 102 and 103, and which lever is keyed to the shaft 81. The lever 103 carries a pin 104 that is received in the slot 52 of the wing 51 of the slide. Thus, as the slide S moves up and down, the shaft 81 is oscillated.

Carried by the sleeve 82 is a ratchet 105. The arm 102, which is drivably mounted on the shaft 81, has pivotally mounted on its free end, as indicated at 106, a spring-biased pawl 107, the free end of which is adapted to engage one of the teeth of the ratchet 105. A locking dog 108 is pivotally mounted on a pin 109 that is carried by the frame wall 80.

It is evident that on downward movement of the slide S the shaft 81 is rotated, but this motion is not imparted to the sleeve 82 because the pawl 107 simply rides over the teeth of the ratchet 105. Moreover, the dog 108 definitely prevents rotation of the sleeve 82 in a counter-clockwise direction (speaking with reference to the showing of Figure 5). However, upon upward movement of the slide S, the pawl 107 engages one of the teeth of the ratchet 105 to rotate the sleeve 82 in a clockwise direction (speaking with reference to the showing of Figure 5).

Referring now more particularly to Figures 9, 10, and 11, a lever 110 is shown as being pivotally mounted on a pin 111 that is fixedly secured to the frame F. The outer free end of this lever is slotted as shown at 112, with the slot receiving the upwardly projecting portion of pin 42 that is carried by the pusher 41. A cam-follower in the form of a roller 113 is mounted on a pin 114 that extends upwardly from the lever 110 and engages the four-lobe cam 85. An abutment pin 115 is adjustably mounted in a block 116 that is carried on the upper face of the lever 110. The inner end of this abutment pin 115 is adapted to be engaged by the cam 86. The cams 85 and 86, together with the cam-follower 113 and abutment pin 115 through the lever 110, control and cause the operation of the pusher 41.

Operation

A complete operation will be described, beginning with the downstroke. It will be understood that, upon the start of a downstroke of the slide S, a length of wire will have been fed into the machine upon the termination of the previous cycle. This length of wire will extend across the top of the mandrel in the manner depicted in Figure 5.

During the downward stroke, the sleeve 82 is held against rotation by the dog 108. However, the shaft 81 is rotated. As this rotation commences, the cam 86 leaves the end of the abutment pin 115, thus permitting the spring 40 to urge the pusher 41 inwardly so that its inner end edge engages the edge of the wire 91 under pressure.

As downward movement of the slide is continued, the roller 74 of the pressure bar rides into the recess 50. This renders the spring 79 effective to force the rib 75 downwardly against the top face of the wire. The wire is now firmly held under pressure from both directions. As downward motion is further continued, the shear elements

55 and 57 cooperate to cut off a proper length of the wire. Further downward movement causes the members 57 and 58 to function as forming elements which shape the wire into the form of the finished staple, which is the conventional U-shaped construction. As the downward stroke is completed, the arm 63 of the bell-crank release 62 engages the abutment pin 65 to set the bell crank in the position in which the free end of the arm 64 will engage the shoulder 98 of the pawl 66 at the end of the upstroke.

10 At the start of the upstroke, the four-lobe cam 85 leaves the cam-follower 113. However, at this point the pusher 41 cannot move inwardly because the pressure bar P is firmly holding the formed staple. However, when the slide moves upwardly sufficiently far to cause the roller 74 to ride out of the recess 50, the pressure bar leaves the formed staple, and the pusher 41 then moves this formed staple inwardly towards the head of the machine, thus moving the entire line of staples and one staple at the end of the line into the head 10. The line of formed staples is held on the mandrel M by a leaf spring 7 that is secured to the underside of the frame wall 29.

As this upward motion of the slide takes place, the sleeve 82 is rotated to cock or charge the spring 99. At the same time, the rotation of the sleeve causes the four-lobe cam to begin the retraction of the pusher. This pusher must be gotten out of the way so that a new length of wire may be fed into the machine.

30 As the upward motion of the slide is continued, the end 64 of the bell-crank 62 engages the shoulder 98 of the pawl 66 to knock the latter out of engagement with the shoulder 93 of the ratchet 92. This permits the drum to be rotated under the influence of the spring 90°. When the free end of the pawl 66 clears one of the shoulders 93, it is again urged inwardly by the spring 95 so as to engage the next shoulder 93 and thus accurately limit rotation of the drum to 90°. This 90°-rotation causes the feed wheel 88 to feed exactly the required length of wire to the machine. It is notable that as the pawl 66 is knocked out of engagement with the ratchet 92, the bell crank 62 engages pin 5 and is knocked over past dead center and is held in this position by the spring 67. The pawl 66 is thus free to again be brought into engagement with the next ratchet tooth 93 by the spring 95; while the bell-crank release 62 is again set at the end of the downstroke by the abutment pin 65.

40 After the effective end of the pawl 66 has been knocked out of engagement with one of the ratchet teeth 93, the opposite end of the pawl 66 will have been moved inwardly. In this position it will be engaged by the tooth 93 just released to again set the effective end of the pawl regardless of the action of the spring 95. This affords definite assurance that the drum D will not rotate through more than 90°.

45 The machine is now in condition to have the cycle repeated.

50 While a preferred specific embodiment of the invention is hereinbefore set forth, it is clearly to be understood that the invention is not to be limited to the exact constructions, mechanisms, and devices illustrated and described, because various modifications of these details may be provided in putting the invention into practice within the purview of the appended claims.

55 What is claimed is:

1. In a staple-forming machine, a frame, a mandrel mounted in said frame, a slide mounted for reciprocal movement in said frame, power means for actuating said slide, wire-feeding means operatively connected to said slide and adapted to feed a length of wire over said mandrel, a pusher slidably mounted on said mandrel and adapted to engage an edge of said wire under spring pressure, a pressure bar mounted in said frame and adapted to engage the top face of said wire under spring pressure, cooperating elements of a shear on said slide and

frame, respectively, and staple-forming elements carried by said slide and adapted to cooperate with said mandrel.

2. In a staple-forming machine, a mandrel having a shallow concave top wall and parallel side walls, forming elements adapted to bend a piece of wire over said mandrel into a substantially U-shaped formation including a back and legs, and a pressure bar for forcing the back of the staple into the concave top wall of the mandrel to impart a corresponding curvature thereto.

3. In a staple-forming machine, a mandrel having a shallow concave top wall and parallel side walls, forming elements for bending a piece of wire over said mandrel into substantially a U-shaped formation including a back and legs, a pressure bar for forcing the back of said staple into the concave top wall of the mandrel to impart a corresponding curvature thereto, and adjustable spring means for actuating said pressure bar.

4. In a staple-forming machine, a frame, a mandrel mounted in said frame, a slide mounted for reciprocal movement in said frame, power means for actuating said slide, said slide having a main body portion, one face of which is formed with a recess, wire-feeding means operatively connected to said slide, a pressure bar of bell-crank formation pivotally mounted in said frame and having a rib at the lower front edge thereof adapted to engage the top face of the wire which has been fed into position over said mandrel, spring means normally urging the rib on said pressure bar into engagement with said wire, said pressure bar carrying a roller that cooperates with the main body portion of said slide and the recess therein to cause said pressure bar to operate in synchrony with reciprocation of said slide, cooperating elements of a shear on said slide and frame, respectively, and staple-forming elements carried by said slide and adapted to cooperate with said mandrel.

5. In a staple-forming machine, a frame, a mandrel mounted in said frame, a slide mounted for reciprocal movement in said frame, a shaft rotatably mounted in said frame, an operating connection between said shaft and said slide, a cam carried by said shaft, a spring-biased pusher slidably mounted on said mandrel, a lever pivotally mounted in said frame and connected to said pusher, a cam abutment carried by said lever and adapted to be engaged by said cam, wire-feeding means operatively connected to said shaft, cooperating elements of a shear on said slide and frame, respectively, and forming elements carried by said slide and adapted for cooperation with said mandrel.

6. In a staple-forming machine, a frame, a mandrel mounted in said frame, a slide mounted for reciprocal movement in said frame, power means for actuating said slide, a shaft journaled in said frame, an operating connection between said shaft and said slide, a cam carried by said shaft, a sleeve rotatably mounted on said shaft and having one end formed as a cam surface, a one-way driving connection between said shaft and said sleeve whereby said sleeve is rotated only on one stroke of said slide, a spring-biased pusher slidably mounted on said mandrel, a lever pivotally mounted on said frame and operatively connected to said pusher, a cam-follower mounted on said lever adapted to cooperate with the cam surface on said sleeve, an abutment pin on said lever adapted to cooperate with the cam on said shaft, wire-feeding means operatively connected to said sleeve, cooperating elements of a shear on said slide and frame, respectively, and staple-forming elements on said slide adapted to cooperate with said mandrel.

7. In a staple-forming machine, a frame, a mandrel mounted on said frame, a slide mounted for reciprocal movement in said frame, power means for actuating said slide, a shaft journaled in said frame and operatively connected to said slide, a sleeve rotatably mounted on said shaft, ratchet-and-pawl mechanism for operatively connecting said sleeve to said shaft for rotation in one direction only, a drum rotatably mounted on said sleeve,

a wire-feeding wheel carried by said drum, a ratchet also carried by said drum, a wound spring having one end anchored to said drum and the other end to said sleeve, a holding pawl pivotally mounted on said frame and having one end that is spring-biased into engagement with one of the ratchet teeth on said drum and an abutment shoulder, and a drum release carried by said slide and adapted to engage said abutment shoulder to move said pawl out of engagement with the ratchet tooth with which it engages to permit said drum to be rotated under the influence of said wound spring and feed a length of wire into position over said mandrel.

8. In a staple-forming machine including a frame and a slide mounted for reciprocal movement therein, wire-feeding mechanism comprising: a shaft journaled in said frame, an operating connection between said shaft and said slide, a sleeve rotatably mounted on said shaft, a ratchet-and-pawl mechanism on said sleeve and shaft, respectively, for rotating said sleeve from said shaft in one direction only, a drum rotatably mounted on said sleeve, a roller cooperating with said drum in receiving wire to be fed between said drum and roller, a clock spring having one end anchored to said drum and the other end anchored to said sleeve, a feed wheel carried by said drum, a ratchet carried by said drum and having a plurality of teeth, a holding pawl pivotally mounted on said frame and having one end adapted to engage any one of said ratchet teeth on the drum, a spring associated with the other end of said pawl and mounted on said frame for urging said pawl end into position in which it is engaged by a ratchet tooth on the drum, an abutment shoulder on said pawl, and a drum release mounted on said slide and adapted to engage said abutment shoulder to knock said pawl out of drum-holding position.

35. 9. In a staple-forming machine, a frame, a mandrel mounted in said frame, a slide mounted for reciprocal movement in said frame, power means for actuating said slide, a shaft journaled in said frame, a driving connection between said shaft and said slide, a cam carried by said shaft, a sleeve rotatably mounted on said shaft and having one end formed as a cam surface, a ratchet carried by said sleeve and having four ratchet teeth, a dog pivotally mounted on said frame and having an effective end adapted to engage one of said ratchet teeth to prevent rotation of said sleeve in one direction, a pawl carried by said shaft and adapted to engage one of said ratchet teeth to rotate said sleeve from said shaft as said shaft rotates in the opposite direction, a drum rotatably mounted on said sleeve, a clock spring having one end anchored to said drum and the other end to said sleeve, a wire-feeding wheel carried by said drum, a second ratchet carried by said drum having ratchet teeth, a second pawl pivotally mounted on said frame and having an effective end spring-biased into position engaging one of the teeth of said second ratchet, an abutment shoulder on said pawl, a spring-biased bell crank mounted on said slide and having one arm adapted to engage said abutment shoulder to knock the effective end of said pawl out of holding engagement with said second ratchet, a spring-biased pusher slidably mounted on said mandrel, a lever having one end pivotally mounted in said frame and the other end connected to said pusher, a cam-follower on said lever adapted to engage the cam surface on said sleeve, an abutment pin on said lever adapted to be engaged by the cam on said shaft, cooperating elements of a shear on said slide and frame, respectively, and staple-forming elements carried by said slide and adapted to cooperate with said mandrel.

10. In a staple-forming machine, a frame, a mandrel mounted in said frame, a slide mounted for reciprocal movement in said frame, power means for actuating said slide, a shaft journaled in said frame, a driving connection between said shaft and said slide a cam carried by said shaft, a sleeve rotatably mounted on said shaft and having one end formed as a cam surface, a ratchet carried by said sleeve and having two ratchet teeth, a dog

pivottally mounted on said frame and having an effective end adapted to engage one of said ratchet teeth to prevent rotation of said sleeve in one direction, a pawl carried by said shaft and adapted to engage one of said ratchet teeth to rotate said sleeve from said shaft as said shaft rotates in the opposite direction, a drum rotatably mounted on said sleeve, a clock spring having one end anchored to said drum and the other end to said sleeve, a wire-feeding wheel carried by said drum, a second ratchet carried by said drum having ratchet teeth, a second pawl pivottally mounted on said frame and having an effective end spring-biased into position engaging one of the teeth of said second ratchet, an abutment shoulder on said pawl, a spring-biased bell crank mounted on said slide and having one arm adapted to engage said abutment shoulder to knock the effective end of said pawl out of holding engagement with said second ratchet, a spring-biased pusher slidably mounted on said mandrel, a lever having one end pivottally mounted in said frame and the other end connected to said pusher, a cam-follower on said lever adapted to engage the cam surface on said sleeve, an abutment pin on said lever adapted to be engaged by the cam on said shaft, cooperating elements of a shear on said slide and frame, respectively, staple-forming elements carried by said slide and adapted to cooperate with said mandrel, a pressure bar in the form of a bell crank pivottally mounted in said frame and having a rib at its lower front edge adapted to engage the wire which has been fed over said mandrel, and an adjustable spring for actuating said pressure bar, said pressure bar and slide having cooperating elements controlling the operation of said pressure bar.

11. In a staple-forming machine including a reciprocal slide and a spring-biased wire-feeding drum normally held against feeding rotation, a roller cooperating with said

drum in receiving wire to be fed between said drum and roller, a release in the form of a spring-biased bell crank mounted on said slide and having one arm adapted to affect said drum to cause its feeding rotation.

5 12. In a staple-forming machine, a frame, a slide reciprocally mounted in said frame, power means for actuating said slide, a drum, a wire-feeding wheel carried by said drum, a roller cooperating with said wheel in receiving a wire to be fed between said wheel and roller, ratchet mechanism including a pawl normally holding said drum against rotation in a feeding direction, a clock spring associated with said drum and adapted to be loaded upon movement of said slide, a spring-biased bell crank mounted on said slide and having one arm adapted to engage said pawl to release said drum and permit feeding rotation of said feed wheel, and an abutment pin carried by said frame and adapted to be engaged by the other arm of said bell crank to set said bell crank into position in which the first-mentioned arm will engage said pawl.
